CLAIM

The ornamental design for a folding bed, as shown and described.

DESCRIPTION

FIG. 1 is a front perspective view of a folding bed, showing our new design in a first configuration of use;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the folding bed, shown in a second configuration of use; and,

FIG. 10 is a front perspective view, shown in a folded configuration.

The broken lines shown in the drawings depict portions of the folding bed that form no part of the claimed design.

1 Claim, 10 Drawing Sheets
